UNITED STATES PATENT OFFICE.

GEORGE A. SMITH, OF SAN FRANCISCO, CALIFORNIA.

DAVENPORT-BED.

1,287,486.

Specification of Letters Patent. Patented Dec. 10, 1918.

Application filed June 24, 1916. Serial No. 105,741.

To all whom it may concern:

Be it known that I, GEORGE A. SMITH, a citizen of the United States, residing at the city and county of San Francisco and State of California, have invented new and useful Improvements in Davenport-Beds, of which the following is a specification.

This invention relates to davenport beds and has for its object to simplify and improve the construction and operation of such devices with a view to obtain an easily operable davenport bed, of standard size, both as to the bed and settee portions, and wherein the bed clothing will be folded in such a way as to prevent crushing thereof or injury to the mattress.

In carrying out this object, I employ a davenport or settee frame, having a hinged seat and back; a bed frame in three sections hinged together, the head and intermediate sections being adapted to fold into parallel, vertical positions, back to back behind the back rest of the davenport and the foot section being foldable into position beneath the seat, top-side up, and novel and improved connections for the parts, whereby to simplify the construction and facilitate the ready operation of the device.

One form which my invention may assume is exemplified in the following description, and illustrated in the accompanying drawings, in which—

Figure 1 shows a vertical, longitudinal, sectional view of the device embodying my invention, with parts in extended position.

Fig. 2 shows a similar view with the parts in folded position.

Fig. 3 shows a front elevation of the device shown in Fig. 2.

Fig. 4 shows a front elevation of the device shown in Fig. 1.

Figs. 5 and 6 show details of the supporting member carried between the head and intermediate sections of the bed.

In the drawings, I have shown a davenport or settee frame 10 of popular size and comprising side pieces 11 and back portion 12 with intermediate connections. A cushioned seat 13 is hinged at its forward end to the side pieces by means of pivot links 14, and carries upwardly and rearwardly extending side pieces 15 which by engagement with lugs 16 on the rear frame section, serve to support one end of the seat in folded position.

The side pieces 15 also carry rigid legs 17 for engagement with the floor, whereby to support the seat when the latter is extended and inverted. A foot board 10^a on the davenport frame stays the links 14 when the seat is in extended position. A back-rest 18 of any suitable construction is hinged in any desired manner to the top of the frame section 12 and swings from a downwardly extending position, where it cooperates with the seat to close the davenport, into an up-standing position where it exposes the back of the davenport.

The bed frame comprises three sections, namely, a head section 19, an intermediate section 20 and a foot section 21, each comprising a rigid frame carrying a portion of a wire mattress 22. The head and intermediate sections are hinged together to fold back to back in a vertical position and the foot and intermediate sections are hinged together to fold substantially at right angles, as shown in Fig. 2. The head section is supported at its forward end by rigid legs 23 pivotally connected to brackets 24 carried on the rear frame section 12. Pivoted near the joint between the head and intermediate sections are pendant legs 25, guided and held in vertical position by means of pins 26 on the adjacent sections. When the sections are folded, these legs extend downwardly between the two sections, and when extended, the legs occupy a right-angular position and rest upon supporting brackets or shelves 27 secured to the side portions 11 of the davenport frame. The foot section and the adjacent end of the intermediate section, when in extended position, rest upon the side pieces 15 of the inverted seat and are slideable thereon by reason of connections hereinafter described. Between the foot section and the side pieces 15, I provide bent links 28 pivotally connected to the said foot section, intermediate the ends thereof, and having pintles 28^a, working in upwardly and rearwardly inclined slots or tracks 29, on the said side bars. When the seat is in folded position, the links 28 are at the lower and forward end of the slots and serve to support the foot section, as shown in Fig. 2. In moving the parts into extended position, the links 28 remain at the same end of the slot until the seat comes to rest. This places the bed sections in the position shown in dotted

lines in Fig. 1, where the said sections occupy a zig-zag arrangement. Thereafter, by pulling on handles 30 attached to the foot section, the links slide forwardly in the slots to the 5 opposite ends thereof, at the same time swinging about their pivotal connections with the foot section and slots, to permit the bed sections to occupy positions in alignment with each other, the pendant legs 25 10 meanwhile coming to rest upon the supports 27. To close or fold the bed, the operator lifts up the outer end of the foot section, which through a leverage afforded by the links 28, transmits a downward movement to 15 the adjacent end of the intermediate section, both of said sections being spaced above the side pieces 15 of the seat by means of blocks 22^a and 21^a. Thereby the hinge joint between the head and intermediate sections is 20 broken, and thereafter by pushing forwardly, the parts fold in the reverse order of unfolding.

The device shown and described herein, operates with great ease and rapidity. A 25 strap or hand hold 31 is preferably provided on the rear edge of the seat, and this is exposed when the back is swung upwardly, so that the operator, by pulling on the strap, can easily overturn the seat. It will be noted 30 that there is a minimum of weight imposed upon the seat when turning the same, none of the bed sections or bed clothing turning with the seat. The foot section is never inverted but retains at all times its position 35 topside up. The turning movement of the seat merely raises the foot section and draws it forwardly, and inasmuch as a long leverage is afforded for this operation, it is evident that a minimum of effort is required to 40 un-fold the bed. After the seat comes to rest, the movement of the bed sections into alignment is almost automatic, since the position of the head and intermediate sections causes a thrust in a direction to move the foot section 45 forwardly and align the whole. The pivotal movement of the seat is about the connections with the links 14, and at the end of 90° the said links strike the edge of the seat and thereafter the movement is about 50 the connections between the links and the stationary frame. This latter movement thrusts the seat forwardly and allows it to drop to a lower plane. The pendant legs 25 support the bed intermediately, and the 55 guides 26 insure the engagement of the said legs with the supports 27 and at the same time permit folding of the legs with respect to the adjacent sections. The head and intermediate sections fold back to back and 60 therefore the bedding is not crushed as in other constructions. Preferably I use a mattress 32 with a joint or hinge in line between the head and intermediate sections and thereby I am enabled to prevent severe bending of 65 the mattress. By having two vertical sec-

tions in folded position, less height is required for the back frame 12, which receives them. Other constructions employing a single vertical member at the back, find it necessary to extend the frame to a height greater than popular size and design will permit.

The present construction lends itself to ready and quick assembling. It will be noted that there are but two permanent connections between the bed frame and the davenport frame, namely, the links 28 in the slots 29 and the standards 23 on the brackets 24. Accordingly, I am enabled to provide a knock-down construction by simply providing the slots 29 with gateways 33 in the upper edges to permit removal of the pintles 28^a, and employing flattened or rectangular pintles 34 on the standards 23 and recesses 35 in the brackets 24 to receive said pintles, said 85 recesses being provided with enlargements at their inner ends to permit turning of the pintles therein. Only when the head section is moved to extended position, will the pintles 34 pass through the said recesses, the 90 connections being at all other times locked. It will also be noted that the steel or metal work herein, which includes the bed frame and operative connections therefor, are few and easily assembled, and since it is the custom in this art for one manufacturer to supply the metal parts to another manufacturer, who does the woodwork and assembling, it is obvious that the simplicity of attachment of the metal parts to the woodwork is an 95 important consideration.

While I have shown herein and described but one form of my invention, it will be understood nevertheless, that the same is susceptible of modification, and therefore many 105 changes in the construction and arrangement of the several parts may be employed, without departing from the spirit thereof, as disclosed in the appended claims.

Having thus described my invention, what 110 I claim and desire to secure by Letters Patent is—

1. In a davenport bed, a frame having a pivoted and overturning seat and movable back-rest, a folding bed therein operable by 115 turning said seat comprising a head, intermediate and foot sections hinged together, the head and intermediate sections being foldable behind the back-rest and the foot section being foldable beneath the seat. 120

2. In a davenport bed, a frame having a reversible seat and movable back-rest, a folding bed therein comprising a head, intermediate and foot sections hinged together, the head and intermediate sections being foldable behind the back-rest, the foot section being foldable beneath the seat and connections between the seat and foot section for folding and extending the latter. 125

3. In a davenport bed, a frame having a 130

pivoted and overturning seat and a movable back rest, a folding bed therein connected to and operably effected by turning said seat and comprising a head, intermediate and 5 foot sections hinged together, the head and intermediate sections being foldable back to back behind the back rest and the foot section being foldable beneath the seat without inversion, said sections being so positioned 10 relatively to the frame, back rest and seat when in folded position as to provide sufficient room for bed clothing thereon.

4. In a davenport bed, a frame having a pivoted and overturning seat and a movable back rest, a folding bed therein connected to and operably effected by turning the seat and comprising a head, intermediate and foot sections hinged together, the head and intermediate sections being foldable behind 20 the back rest and the foot section being foldable beneath the seat, the connections between the seat and bed frame including swinging links connected to the foot section and operable to permit the latter to 25 move from beneath to above the seat in unfolding without reversing its position.

5. In a davenport bed, a frame having a pivoted and overturning seat and a movable back rest, a folding bed therein connected to and operably effected by turning the seat 30 and comprising a head and intermediate sections hinged together and foldable back to back behind the back rest leaving sufficient space on opposite sides to accommodate a 35 mattress.

6. In a davenport bed, a frame having a pivoted and overturning seat and a movable back rest, a folding bed therein connected to and operably effected by turning the seat 40 and comprising a head and intermediate sections hinged together and foldable back to back behind the back rest, a pendant leg pivoted between said sections for supporting them in extended position and foldable therewith, a foot section hinged to the 45 intermediate section and connections between the seat and foot section controlling the latter and operable to position the same beneath the seat when the latter is folded.

50 7. In a davenport bed, a frame having a reversible seat, and a folding bed therein having a foot section carried by said seat and movable from a position beneath the folded seat to a position above the inverted 55 seat when the latter is unfolded, without inversion and swinging links connected between said seat and foot section for controlling the latter.

8. In a davenport bed, a frame having a 60 reversible seat, and a folding bed therein having a foot section carried by said seat and movable from a position beneath the folded seat to a position above the inverted seat when the latter is unfolded, without inversion, swinging link connections between 65

the foot section and seat for controlling the movement of said section and slidably connecting between said links and seat to permit the foot section to be extended forwardly when the seat is inverted. 70

9. In a davenport bed, a frame, a reversible seat thereon, connections between the seat and frame for thrusting said seat forwardly when it is inverted, legs on said seat for supporting the same in inverted 75 position, a folding bed supported in part by said inverted seat, said bed comprising head, intermediate and foot sections hinged together, the head and intermediate sections being foldable vertically back to back in the 80 rear of the frame and the foot section being carried at all times by the seat and suspended beneath the same in folded position.

10. In a davenport bed, a frame, a reversible seat thereon, connections between 85 the seat and frame for thrusting said seat forwardly when it is inverted, legs on said seat for supporting the same in inverted position, a folding bed supported in part by said inverted seat, said bed comprising head, 90 intermediate and foot sections hinged together, the head and intermediate sections being foldable vertically back to back in the rear of the frame, the foot section being carried by the seat and suspended beneath 95 the same in folded position and connections between the foot section and seat, whereby turning of the seat moves the foot section forwardly and upwardly in a substantially horizontal plane to a position above the seat. 100

11. In a davenport bed, a frame, a reversible seat thereon, connections between the seat and frame for thrusting said seat forwardly when it is inverted, legs on said seat for supporting the same in inverted position, a folding bed supported in part by said inverted seat, said bed comprising head, intermediate and foot sections hinged together, the head and intermediate sections being foldable vertically back to back in the 105 rear of the frame, the foot section being carried by the seat and suspended beneath the same in folded position and connections between the foot section and seat, whereby turning of the seat moves the foot section 110 forwardly and upwardly in a substantially horizontal plane to a position above the seat, said connections being also operable to permit the foot section and the others to be 115 moved into alignment. 120

12. In a davenport bed, a frame, a reversible seat thereon, connections between the seat and frame for thrusting said seat forwardly when it is inverted, legs on said seat for supporting the same in inverted 125 position, a folding bed supported in part by said inverted seat, said bed comprising head, intermediate and foot sections hinged together, the head and intermediate sections being foldable vertically back to back in the 130

rear of the frame, the foot section being carried by the seat and suspended beneath the same in folded position and pivotal and slideable connections between the foot section 5 and the seat, whereby turning of the seat moves the foot section forwardly and upwardly in a substantially horizontal plane to a position above the seat, whereupon the said foot section may be drawn forwardly

upon the seat to bring all of the sections 10 into alinement.

In testimony whereof I have hereunto set my hand in the presence of two subscribing witnesses,

GEORGE A. SMITH.
